(57) CLAIM

The ornamental design for a storage cabinet, as shown and described.

DESCRIPTION

FIG. 1 is an upper perspective view of a storage cabinet showing my new design; FIG. 2 is a lower perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 2; FIG. 11 is an enlarged view of portion 11 shown in FIG. 2; and,

FIG. 12 is another perspective view of the storage cabinet of FIG. 1, shown in an alternate configuration. The dash-dash broken lines in the drawings depict portions of the storage cabinet that form no part of the claimed design. The dot-dash broken lines represent boundaries of the enlarged portion that form no part of the claimed design.

1 Claim, 12 Drawing Sheets
